FOOT MEASURING DEVICE

Herbert H. Di Piero, Youngstown, Ohio

Application July 13, 1953, Serial No. 25,894

Term of patent 14 years

(Cl. D52—1)

To all whom it may concern:

Be it known that I, Herbert H. Di Piero, a citizen of the United States, residing at Youngstown, in the county of Mahoning and State of Ohio, have invented a new, original, and ornamental Design for a Foot Measuring Device, of which the following is a specification, reference being had to the accompanying drawing, forming a part thereof.

Figure 1 is a perspective view of a foot measuring device, showing my new design.

Figure 2 is a perspective view of the bottom portion of the foot measuring device.

The characteristic features of applicant's design reside in the longitudinally slotted angular portion thereof.

I claim:

The ornamental design for a foot measuring device, as shown and described.
